UNITED STATES PATENT OFFICE.

JOHN MEHL, JR., OF JERSEY CITY, NEW JERSEY.

DESIGN FOR A COVER FOR POCKET-BOOKS OR CARD-CASES.

SPECIFICATION forming part of Design No. 28,173, dated January 18, 1898.

Application filed December 14, 1897. Serial No. 661,902. Term of patent 3½ years.

To all whom it may concern:

Be it known that I, JOHN MEHL, Jr., a citizen of the United States, residing at Jersey City, in the county of Hudson and State of New Jersey, have invented and produced a new and original Design for the Covers of Pocket-Books or Card-Cases, of which the following is a specification, reference being had to the accompanying drawings, forming a part thereof, in which—

Figure 1 is a plan view of a pocket-book or card-case cover embodying the features of my design, and Fig. 2 is a section on the line 2—2 of Fig. 1.

The leading feature of the design consists in embossed corner-panels A and B, having two straight outer edges a and a' at angles to each other and a waved inner edge connecting the outer edges. The waved edge of each

panel is decorated with a bead a^4 , and the detail formation of the waved edge of each panel is that of two shallow scallops b and b' , meeting at the center of the panel, and partial scallops b^2 , extending from the full scallops to the outer edges a and a' of the cover.

The minor feature of the design consists in depressed lines b^3 , which connect with the waved edges of the panels at the junction of the scallops and converge at the intersection of the two outer sections a and a' of the panels.

I claim—

The design for the cover for pocket-books and card-cases herein shown and described.

JOHN MEHL, JR.
